FIG. 4

INVENTOR.
VICTOR H. HURT
BY *Victor H. Hurt*

ATTORNEY

UNITED STATES PATENT OFFICE

2,404,729

WATER TOY

Victor H. Hurt, Cranston, R. I., assignor to United States Rubber Company, New York, N. Y., a corporation of New Jersey

Application May 24, 1944, Serial No. 537,117

5 Claims.

(Cl. 9—17)

1

The present invention relates to inflatable water toys of the type having pontoon-like members at the sides of the toy to provide a stabilized construction, and the invention relates more particularly to an improvement in water toys of the type disclosed in the Hubbell Patent No. 1,851,768.

The Hubbell patent is directed to an inflatable water toy such as a swan, having pontoon-like stabilizing means secured to each side of the swan's body at the lower portion thereof to cause the swan to remain in an upright or natural position when it floats on the water with only a small portion of the body submerged. This Hubbell toy, however, is not stable in water when the body is largely submerged.

The present invention provides a rideable toy designed to be ridden in water by a child or adult, and provides a mount that is stable when the greater portion of the toy is submerged under the weight of the rider.

The rideable water toy contemplated by the present invention preferably resembles in appearance a four-legged animal, such for example, as a horse, and has a body, and four legs extending downwardly from the body, but each leg terminates in a large oblate spheroidal or balloon-like member. These legs will support the weight of the inflated toy, whether it stands on the ground or on the surface of the water, and the balloon-like members act as stabilizing pontoons at each side of the toy when the toy is partly or largely submerged.

One important feature of the present invention resides in the arrangement of the legs and the large balloon-like members attached thereto, so that as the body of the toy is submerged the legs will bend outwardly and upwardly to permit the buoyant balloon-like members to rise at the sides of the toy to the approximate height of the upper surface or back of the body of the toy, to thereby render the toy stable when it is nearly submerged by the weight of a person riding the same.

Another feature of the present invention resides in an inflated water toy resembling a four-legged animal and constructed so that when a person sits on the back of such toy in the water, his legs will hang downwardly in the clearance space between the front and rear legs of the toy. A further feature of the present invention resides in rounded inflated legs which attach the buoyant balloon-like members to the body of the toy so that these legs, when the toy is inflated will be stiff enough to support the weight of the animal-like toy when it stands on land, and when the toy is forced

2

downwardly in the water under the weight of the load, the relatively stiff legs will bend outwardly and upwardly under the buoyancy of the balloon-like members. This will help to maintain the toy in a stable condition whether it is submerged to a small or large degree.

The above and other features of the present invention will be more fully understood from the following description when read in connection with the accompanying drawing wherein:

Fig. 1 is a perspective view of the rideable water toy of the present invention shown largely submerged in water and with a person sitting astride the back of the toy.

Fig. 2 is a side view of the inflated toy of Fig. 1 shown standing on the ground upon its four legs; Fig. 3 is a side view of the toy of Fig. 1 shown submerged to a considerable degree, and; Fig. 4 is a front view of Fig. 3.

20 The rideable inflated toy constructed in accordance with the present invention may be made to resemble any one of a large number of four-legged animals in appearance, and one good construction resides in the inflatable horse shown in the drawing and which has a body 10, a head 11, front legs 12 each of which terminates in a large balloon-like or oblate spheroidal member 13, and rear legs 14 each of which terminates in a similar balloon-like or oblate spheroidal member 15. The toy also 30 preferably has the tail 16, and the air inlet valve 17 of usual construction located at any desired point for inflating and deflating the toy. The entire toy may be formed of sheet rubber or of rubberized fabric.

35 The legs 12 and 14 preferably have the form of hollow rounded tubes that communicate with the interior of the body 10 so that when the body is inflated the legs and the balloon-like members formed integrally with the legs will also be inflated. As the result of this construction the legs and balloon-like members when fully inflated will be sufficiently stiff to support the weight of the animal-like toy so that it will stand erect in a normal position as shown in Fig. 2 upon the 40 land and in the water, when not weighted down, except that in the water the balloon-like members 13 and 15 will be partly submerged.

If increasing weight is gradually applied to the back of the body 10 of the toy so as to force it down in the water the relatively stiff legs 12 and 14 will spread outwardly away from each other and upwardly in the arc of circles under the buoyancy of the balloon-like members 13 and 15. This will give a large amount of stability to 45 the toy as the body 10 rests on or in the water,

and as the weight upon the back of the toy is increased the relatively stiff legs will gradually bend upwardly substantially as shown in Fig. 4, to a position in which the buoyant balloon-like members rise at the sides of the body 10 to a position approximately as high or slightly higher than the upper surface of the back of the toy animal.

The buoyant pontoon members 13 and 15 will exert a stabilizing effect upon the toy, so long as they are not completely submerged, but when completely submerged lose most of their stabilizing effect. Therefore the construction of the present invention is such that when the water-toy is largely submerged under the weight of the rider as shown in Fig. 1, the balloon-like members 13 and 15 will still be partly out of the water so that if the toy leans to one side or the other the buoyant members at the lower side towards which the toy leans will exert an increasing lifting action upon the toy to restore the same to its even keel. The total displacement of the four members 13 and 15 should preferably equal at least one half that of the body 10 to impart the desired degree of stability to the rideable toy.

It will be seen from the foregoing that when the present four-legged toy is inflated it will stand in a normal condition on its four legs under its own weight, and when ridden in water it will float in a stable manner even when mostly submerged.

Having thus described my invention, what I claim and desire to protect by Letters Patent is:

1. An inflated water toy comprising a body and four flexible legs extending downwardly from the body and terminating in enlarged oblate spheroidal members which are so connected to the body by the legs that as the body is submerged the legs will bend and permit the buoyant oblate and spheroidal members to rise at the sides of the body to the approximate height of the upper surface of said body and thereby increase the stability of the toy when largely submerged.

2. A water toy comprising an inflated body and four inflated rounded legs extending outwardly and downwardly from the body and terminating in enlarged oblate spheroidal members which are yieldingly held in spaced relation to the body by said inflated legs which are adapted to bend as the body is submerged, the total lengths of the legs and enlarged members being sufficient to rise at the sides of the body to the approximate height of the upper surface of the body.

3. A water toy resembling an animal and comprising an inflated body and four inflated legs extending outwardly and downwardly from the body and terminating in elongated oblate spheroidal member the lengths of the legs and the members being such that as the body is submerged the legs will fold toward the surface of the water and the members will rise at the sides of the body to the approximate height of the upper surface of the body.

4. A water toy resembling a four-legged animal and comprising an inflated body having attached thereto a head and four legs extending downwardly from the body near its opposite ends, and each leg terminating in a large balloon-shape member which is flexibly connected to the body by its leg, and the combined length of the leg and balloon-shape member is such that as the body is submerged said member will rise to the approximate height of the upper surface of the body and thereby stabilize the toy when it is largely submerged by the weight of a person riding the toy.

5. A water toy comprising an inflated body and inflated rounded legs extending downwardly from the body and terminating in large balloon-shape members which are yieldingly held in spaced relation to the body by the inflated legs that are stiff enough to support the weight of the body without bending, but are adapted to bend upwardly as the body is submerged by added weight and permit the balloon-like members to rise at the sides of the body to the approximate height of the upper surface of the body.
